UNITED STATES PATENT OFFICE.

EMIL C. LOETSCHER, OF DUBUQUE, IOWA.

WINDOW-SASH CONSTRUCTION.

Application filed April 28, 1927. Serial No. 187,261.

This invention relates to wood frames and the like, and particularly to wood window sashes.

Heretofore, it has been customary in manufacturing wood window sashes to connect the top and bottom cross rails to the side stiles by mortise and tenon joints interlocked by nails or the like. This method of joining the elements does not make a very firm sash and the latter may easily be forced out of square by slight pressure on the corners, due to the fact that the nails do not obtain a firm bearing on the wood on account of being of such small diameter. The elements of the sashes, as heretofore made, are also difficult to assemble.

The primary object of the present invention is to improve the construction of window sashes and the like, to provide stronger joints for the same, and to make it possible to dispense with the pinning operation and the assembling of the sash parts by hand, preparatory for the pinning operation.

A still further object is to furnish a window sash, the side stiles of which may be joined and interlocked with the cross rails by simply moving the side stiles toward each other while they are engaged with the cross rails.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings,

Fig. 1 is a top plan view of a portion of a window sash made in accordance with my invention.

Fig. 2 is an elevation of the same.

Fig. 3 is a bottom plan view thereof.

Fig. 4 is an end view of the same.

Fig. 5 is an elevation of a threaded dowel pin forming part of the invention.

Fig. 6 is a view similar to Fig. 4, but showing a modification.

Fig. 7 is an enlarged vertical sectional view of the frame, taken on line 7—7 of Fig. 2.

In the drawing, 1 designates the bottom rail, 2 the top or check rail, and 3 a side stile

of a window sash formed in accordance with my invention.

As shown in Fig. 3, the bottom rail is provided at each end with a vertical groove 4 which interlocks with a vertical rib 5 on the stile when the parts are connected.

The stile is connected to the bottom rail by threaded dowel pins 6, one of which is shown in Fig. 5. This pin may be made of metal or wood, preferably the latter, and it consists of a central portion 7 from which extends threaded pins 8, the threads of which are of opposite pitch and made very steep, at least 45 degrees, so that as the side stile is pressed toward the rail, the dowel will automatically turn in the rail and stile, and thus interlock the parts together.

This form of dowel facilitates the rapid assembly of the parts, and when the parts have been forced to the position shown in Fig. 2, the dowel pins are concealed and form interlocking means which effectively prevent the parts from moving away from each other.

The top of the stile is provided with spaced tenons or tongues 9, 10, the former of which is provided with a substantially horizontal projecting bead or semi-cylindrical rib 11.

The end of the check rail 2 is provided with somewhat similar tenons 12 and 13 which engage the tenons 9 and 10 when the parts are assembled. The tenon 12 is provided with a substantially horizontally disposed semi-cylindrical recess 14 to receive the rib 11, and this recess and rib prevents the rail 2 from moving upwardly relatively to the stile, after the parts are assembled.

At this corner of the sash, the parts are also interlocked together by one of the dowel pins 6, which preferably enters the tenon 9 when the stile is forced toward the side rail.

Instead of making the rib and recess of semi-cylindrical formation, as shown in Figs. 4 and 7, they may be made angular, as at 15 in Fig. 6. However, in either case, the rib on the side of the tenon 9 will effectively prevent the top cross rail from rising relatively to the side stile.

In assembling the parts, the dowels 6 are first driven slightly into the rails 1 and 2, and then the stile is placed against the outer ends

of the dowels and forced towards the rails. This causes the dowels to automatically turn in the wood, and to draw the parts together as the pressure increases.

5 Instead of driving the dowel in straight, that is, at right angles to the end of a cross rail, it may be tilted slightly in one direction or the other, and it will then have a tendency to hold the joint rigid in two directions instead of one.

Furthermore, the rib 11 and groove 14 may be inclined slightly if desired, so that as the stile is pressed on to the check rail, there will be a tendency for the check rail to draw closer 15 to the stile, making a tight joint where the rail meets the latter.

Of course, the dowels and abutting surfaces of the parts may be provided with glue before assembly, and this will facilitate the permanency of the joints. It is to be noted that the construction which I have devised permits, to some extent, the making of the parts 20 on machines now in use, and allows more rapid assembly by machine than was heretofore possible. In addition, the parts, after assembly, remain firm and the joints are not easily loosened.

From the foregoing, it is believed that the construction, operation and advantages of the 30 invention will be apparent to those skilled in the art, and it is obvious that various changes may be made in the details disclosed without departing from the spirit of the invention, as expressed in the claims.

35 What I claim and desire to secure by Letters Patent is:

1. In a frame, a cross rail member and a side stile member, each provided with interengaging tenons, a tenon on one member having a cross rib, and a tenon on the other member having a groove parallel to the rib and adapted to receive said rib, and concealed means for interlocking said tenons together.

2. In a frame, a cross rail member and a side stile member, each of said members having interengaging tenons, a rib on a tenon of one of the members arranged transversely to the latter, a tenon on the other member having a longitudinally disposed groove parallel to the rib and adapted to receive said rib, and concealed means interlocking said tenons together.

3. In a frame, a cross rail and a side stile, the cross rail and side stile having interengaging tenons at their ends, one of said tenons having a transversely disposed rib thereon, and another one of the tenons having a longitudinally disposed groove parallel to the rib and to receive said rib, and a concealed dowel pin connecting the ends of the cross rail and stile and extending longitudinally of the cross rail.

In testimony whereof I affix my signature.
